L. R. WITHERELL AND E. A. WITHERELL, OF GALESBURG, ILLINOIS.

Letters Patent No. 85,155, dated December 22, 1868.

IMPROVED MACHINE FOR WASHING DISHES.

The Schedule referred to in these Letters Patent and making part of the same.

To all whom it may concern:

Be it known that we, L. R. WITHERELL and E. A. WITHERELL, of Galesburg, in the county of Knox, and State of Illinois, have invented certain new and useful Improvements in Dish-Washing Machines; and we do hereby declare that the following is a full, clear, and exact description of the same, reference being had to the accompanying drawings, making a part of this specification, in which—

Figure 1 is a vertical central sectional view.

Figure 2 is a side elevation of a part of the machine.

Figures 3 and 4 are top plans of racks, for carrying dishes, &c., while washing.

Similar letters of reference indicate similar parts in all the drawings.

The nature of this invention relates to improvements in machinery for washing dishes; and

The invention consists in an arrangement of racks for holding dishes, plates, &c., and suitable mechanism for turning them and exposing all sides to the action of boiling water discharged among them through jets in a pipe connected with a force-pump, which is attached to one side of the vessel containing the dishes, and which is operated by the same crank which revolves the racks.

Letter A is a cylindrical-shaped vessel, constructed of any suitable material, and of any desirable size, and provided with lid B, hinged at C, for convenient communication with the inside of the vessel A.

Letter m, fig. 1, is an upright shaft, supported in the socket n, in the bottom of the vessel A, in a manner allowing it to revolve freely.

Letter R is a disk, carried in a horizontal position on the top of shaft m.

Letter F is a shaft, with bearings at P and V", and carrying on its outer end the crank E and handle t, for operating the machine.

Letter G is a worm on the shaft F, gearing with the worm-wheel J, on the shaft m, and communicating the rotary motion of shaft F to the disk R.

Letter T represents racks; a side view shown at fig. 1, and top view of the two styles, shown at figs. 3 and 4. These racks are set on the disk R, and held in place by pins S S, or their equivalent. The style of rack shown at fig. 3 is intended more particularly for dishes, which are stood on their edges in the spaces; while the style at fig. 4 is intended for cups and saucers, and similar-shaped vessels, which may be laid in with their mouths or open ends outward; and the centre spaces T" T", fig. 4, are intended for knives and forks, &c., which may be stood on end.

Letter D represents a case, attached to the side of the vessel A, and contains a double-acting force-pump. The piston l, of the force-pump, is connected with and operated by the cranks E, by means of the connecting-rod w. The suction-pipe y, of the force-pump, communicates with and draws the supply of water from the bottom of the vessel A.

Fig. 2 is a side view of the pump-case D and connections, taken from the point 12, fig. 1.

Letter c", fig. 2, is the discharge-pipe of the pump. This pipe c" communicates, by stop-cock a and pipe e, with the jet-pipe X; the pipe X being provided with any desired series of holes, y y, and standing in a vertical position inside of the vessel A.

Letter h is a hose and nozzle, which may be attached to the discharge-pipe, if desired, and communicates therewith by means of stop-cock a".

Letter P is a cock, for drawing off the water when desired.

The manner of operating my machine is as follows:

The dishes, &c., being placed on the rack, and the rack put in position on the disk R, and water, being heated to 212°, is poured in the vessel A, to fill it nearly to the disk R. The lid B is closed, and the pump, set in operation by the crank E, will draw its supply from the water in the vessel A, and discharge it with great propulsive power through the jets y, in pipe X, among the dishes, the same motion of the crank E revolving at the same time the disk R and rack T, and presenting, by turns, all sides of the articles being washed, to the mechanical action of the propelled jets of boiling water.

The water being many degrees hotter than can be used by hand, and being thrown with much force on all parts of the articles, will thoroughly cleanse them of all dirt and grease, and leave them in a clean, hot, and favorable condition for being taken out and dried.

The greasy water will fall below the disk R, and being there undisturbed, the oil will rise to the top, and the suction-pipe y always obtain the clean water from below, while using the same supply of water over and over.

If desired, the stop-cock a may be closed, and the stop-cock a" opened, and water from the vessel A, through the hose h, be used for washing carriages, windows, &c.

What we claim as our invention, and desire to secure by Letters Patent, is—

1. The arrangement of disk R, rack T, shaft m, socket n, worm-wheel J, shaft F, worm G, and bearings P and r, when used in dish-washing machines, substantially as described, and for the purpose set forth.

2. The combination and arrangement of the vessel A, pump D, pipe X, crank E, shaft F, worm G, pinion J, shaft m, disk R, and rack T, substantially as described, and for the purpose set forth.

Signed at Galesburg, this 7th day of October, 1868.

L. R. WITHERELL.
E. A. WITHERELL.
